UNITED STATES PATENT OFFICE.

WILLIAM B. BUSSARD, OF HUNTINGTON, INDIANA, ASSIGNOR OF ONE-HALF
TO WILLIAM F. STUVER, OF HUNTINGTON, INDIANA.

MOLD.

No. 846,007.

Specification of Letters Patent.

Patented March 5, 1907.

Application filed November 2, 1906. Serial No. 341,778.

To all whom it may concern:

Be it known that I, WILLIAM B. BUSSARD, a citizen of the United States, residing at Huntington, in the county of Huntington and State of Indiana, have invented new and useful Improvements in Molds, of which the following is a specification.

This invention is a mold, and more particularly one for making burial-caskets of artificial stone or concrete.

The object of the invention is to provide a mold embodying simplicity of construction and having extensible walls and a core, so that different-sized caskets can be made in the mold.

In the accompanying drawings, Figure 1 is a central longitudinal section of the invention. Fig. 2 is a horizontal section on the line 2 2 of Fig. 1. Fig. 3 is a longitudinal section of the cover. Figs. 4 and 5 are perspective views of details hereinafter referred to. Fig. 6 is a top plan view of the cover.

Referring specifically to the drawings, 10 denotes the side walls, and 11 the end walls, of the outer part of the mold. In use these are set on a base comprising parallel sills 12, which are connected at their ends by cross-bars 13.

The side walls 10 are in two sections, between which is placed an extension-piece 14 for the purpose of changing the length of the walls, a number of such extension-pieces of different lengths being provided. On the outside of the side wall the extension-piece 35 has lateral extensions 15, which fit between guide-strips 16, secured to the side wall. The extension-piece is held in place by a strap 17, extending across the part 15 and the guide-strips 16. The strap is secured by a wedge-pin 18, which is passed through staples 19, secured to the side walls and extending through holes in the straps.

The end walls 11 are made extensible by means of extension-pieces 21 in the same manner as the side walls. At each end the side walls are formed with shoulders 22, against which the end walls abut and which prevents them from collapsing inwardly. Behind the end walls are rods 23, which extend through the side walls and have threaded ends to receive fastening-nuts 24.

The core is a box-like structure having side walls 25, end walls 26, and a top 27. It is open at the bottom. Secured to the side

walls adjacent their ends are angle-irons 28, 55 having holes to receive staples 29, extending from the end walls. By means of wedge-pins 30, extended through the staples, the end walls will be securely held in position. The side walls also have vertical strips 31 at 60 their ends, forming shoulders against which the end walls abut. The side and end walls of the core are made extensible by extension-pieces 32 and 33, respectively, in the same manner as the walls 10 and 11. Inside the 65 core is a cross-brace 34, having hooked ends 35, engageable with staples 36 on the extension-pieces 32. The top 27 is supported on the strips 31, they being cut away at the top, so that the top 27 will be flush with the top 70 edges of the side and end walls of the core. The outer part of the mold also contains a form for molding a rabbet in the top edge of the casket in which the cover seats. This form is in four parts, consisting of side bars 75 37 and end bars 38, which will be made in various lengths, so as to fit different-sized molds. Each side and end bar has a bead 39, which forms the rabbet herein referred to. On the bottom of the end bars 38 are secured 80 straps 40, having openings to receive staples 41, extending from the bottom of the side bars 37. Wedge-pins 42 are extended through the staples, whereby the side and end bars are securely fastened together. 85 When in position, the side and end bars fit snugly against the side and end walls 10 and 11 and are supported on the sills 12, which are notched, as at 43, to receive the staples 41. The side and end bars 37 and 38 are 90 also braced by a removable bar 44 extending between the end bars and having transverse branches 45 extending between the side bars.

In use the outer part of the mold and the core are adjusted to the desired size and the outer part placed on the sills 12. The parts 37 and 38 are then put in position and fastened together and the braces 44 and 45 applied. The core is then placed inside the mold with its bottom resting on the parts 37 and 38, the side and end walls of the core, however, being spaced from the bead 39. The casket will preferably have a reinforcement of expanded metal or woven wire, (indicated at 46,) which will be placed inside the mold and spaced a proper distance from the walls thereof and the core, so that it will be 100 105

2

embedded in the material. The casket will be molded upside down, the parts 37 and 38 forming the top edge of the casket and the bottom of the casket being at the top of the mold. When the parts herein described have been properly assembled, concrete or artificial stone is filled into the space between the core and the mold in the usual manner. The top of the core is below the top edge of the side bars 10 and 11, so that the material can be placed on top of the core to form the bottom of the casket, a trowel or other suitable tool being used for smoothing the same. If desired, the outer part of the mold can be discarded altogether, the casket being formed by using the core only and plastering the material thereon. After the casket has hardened and it is desired to remove it from the mold the outer part of the mold will first be removed. The casket is then turned over to rest on its bottom, after which the core can be removed. This can be readily done without damage to the casket by removing the extension-pieces 32 and 33.

The mold for the cover comprises a base-board 47 and side and end boards 48 and 49, respectively. A core 50 is secured in an opening in the base-board. The cover has a reinforcement of expanded metal or woven wire, (indicated at 51.). The top of the cover 30 is shaped by a trimming device 52, guided by and run over the top edge of the side and end boards 48 and 49.

I claim—

In a casket-mold, a frame on the inside of the mold for forming the top edge of the casket, said frame comprising separable side and end bars, staples extending from the side bars, straps extending from the end bars and having openings to receive the staples, and locking means entering the staples.

In testimony whereof I have signed my name to this specification in the presence of two subscribing witnesses.

WILLIAM B. BUSSARD.
